REMOVABLE STOP FOR WELL TOOLS

John V. Fredd, Dallas, Tex., assignor to Otis Engineering Corporation, Dallas, Tex., a corporation of Texas

Original application Oct. 9, 1953, Ser. No. 385,248.
Divided and this application Aug. 11, 1958, Ser. No. 754,418

8 Claims. (Cl. 166—219)

This invention relates to new and useful improvements in means for positioning and supporting well devices in well flow conductors such as well tubing or casing or the like, and this application is a division of my co-pending application Serial No. 385,248, filed October 9, 1953.

One object of the invention is to provide a new and improved stop for positioning or supporting well devices in a well flow conductor.

An important object of the invention is to provide a well device adapted to serve as a stop or support for well tools or to close the bore of an open ended well conductor, and which device may be readily and quickly lowered into the well conductor by flexible line lowering means and anchored in position therein at the recess at a collar connecting two adjacent sections of the conductor.

A particular object of the invention is to provide a well device of the character described having stop and supporting dogs which are adapted to be expanded into locking position by a resiliently biased expanding member and wherein means is provided for rendering said expanding member inoperative until the device has been lowered into the well conductor to the desired position.

A further object of the invention is to provide a well device of the character described wherein the means for holding the expanding member against expanding movement with respect to the stop dogs is releasable upon the upward movement of the tool in the well tubing or conductor.

A further object of the invention is to provide a well device of the character described which is designed to provide an obstruction to the passage of well tools downwardly out the open end of the well flow conductor but which also permits substantially full flow of well fluids upwardly through the conductor so that the device does not appreciably restrict the flow of gas and liquids from the well through the conductor.

Additional objects and advantages of the invention will be readily apparent from the reading of the following description of a device constructed in accordance with the invention, and reference to the accompanying drawings thereof, wherein:

Figure 1 is a view partly in elevation and partly in section showing a well device or a stop constructed in accordance with the invention as it appears while being lowered in a tubing string; and

Figure 2 is a view partly in elevation and partly in section showing the stop as it appears locked in position in a well flow conductor.

Referring now to the drawings, the numeral 10 designates a stop having a body 11 which is provided with a threaded upper end 12 by means of which it may be secured to the lower end of a well tool or lowering mechanism. A lock mandrel 13 is threaded in a bore 13a in the lower end of the stop body, and a plunger rod 14 is positioned in said bore and extends downwardly through said mandrel. The lower end of the plunger rod extends below the lock mandrel, and a cup-like dog carrier 15 having an upwardly extending circular wall or lip 15a is

2

secured on said plunger rod below said lock mandrel by a nut 16 threaded on the lower end of the rod. The bore of the dog carrier is provided with an internal annular flange 17 which confines the hooked lower ends 18 of a plurality of stop dogs 19 between the flange and the plunger rod to hold the dogs in position in the carrier.

The upper ends of the dogs are free to move inwardly toward the plunger rod and may engage the frusto-conical expander surface 20 at the lower end of the lock mandrel when the dog carrier and the dogs are moved downwardly relative to the mandrel to the retracted position shown in Figure 1. The beveled inner upper ends 21 of the stop dogs abut the downwardly facing annular wedge and lock shoulder 22 located above the frusto-conical shoulder 20 of the lock mandrel when said stop dogs are moved upwardly relative to said mandrel to expand said dogs to the locking position shown in Figure 2.

The upper end of the plunger rod extends upwardly into the bore 13a of the body and is enlarged and bifurcated to provide a pair of upwardly extending legs 23. A toggle plate 24 is rotatably mounted between the legs on a pin 25 extending through the legs and protrudes laterally into a pair of opposed longitudinal slots 26 and 27 through the walls of the body. One slot 27 is elongated and extends downwardly beyond to the other slot 26. A release dog 28 is pivotally secured at one end by a pin 28a to the toggle plate, and the other end of the release dog is adapted to extend laterally outwardly of the elongated slot 27 beyond the body. A release spring 29 has its opposite ends rigidly secured to the pivot pin 25 and to the release dog and urges the dog outwardly in a clockwise direction for a purpose which will be hereinafter explained.

A link 30 has its opposite ends pivotally secured to the toggle plate 24 and to a link pin 31 extending transversely through the body above the toggle plate. A spring 32 surrounds the upper part of the plunger rod and bears at its upper end against the enlarged upper part of the rod and at its lower end against an internal shoulder 33 in the bore of the lock mandrel 13 whereby the spring urges the plunger rod upwardly relative to the body, and thus biases the carrier 15 and the dogs supported thereby upwardly into expanding engagement with the expander surface 20 at the lower end of the lock mandrel 13.

The link 30 is connected to the toggle plate by a pivot pin 34 displaced from the pin 25 whereby movement of the plunger rod downwardly in the body causes the toggle plate to be rotated in a counter-clockwise direction. The plate is further rotated in a counter-clockwise direction until a stop shoulder 35 on the edge of the toggle plate engages the lower end 36 of the slot 26 in the body. In this position the pivot pin 34 is displaced slightly to the left of the pin 25 and of the link pin 31 attaching the upper end of the link to the body so that the spring 32 biases the plate for rotation in a counter-clockwise direction when the device is in the position of Figure 1.

When the toggle plate 24 is rotated in a clockwise direction through a small angle by the release dog 28, the pivot pin 34 forming the point of pivotal attachment of the lower end of the link 30 to the toggle plate is displaced slightly to the right past a dead center position between the pin 25 and the link pin 31 forming the point of pivotal attachment of the upper end of the link to the body. At this time the toggle plate will be rotated in a clockwise direction to the position shown in Figure 2 by the upward force exerted by the spring 32. The link is provided with a notch 37 intermediate its ends in which the pin 25 is stopped on upward movement of the plunger rod, providing for sufficient rotation of the toggle plate to permit full upward retractive movement of the plunger rod, as shown in Figure 2.

In use, the stop body 11 is supported by the usual

flexible line running and retrieving tools (not shown), and the plunger rod 14 is moved downwardly to the position shown in Figure 1, the toggle plate being rotated in a counter-clockwise direction past dead center until the stop shoulder 35 on the toggle plate engages the lower end or shoulder 36 of the slot 26. The free end of the release dog then projects outwardly and upwardly from the body and is resiliently urged into contact with the wall of the tubing string T as the assembly is lowered therein by means of the flexible line running and retrieving tools. The stop dogs may retract to the position shown in Figure 1 inasmuch as they are not engaged by the frusto-conical expander surface 20. If through jarring or bumping contact of the stop with the tubing wall the stop dogs swing outwardly, they are cammed inwardly by any obstructions or restrictions in the tubing by virtue of the pivotal confinement of their lower ends within the internal flange 17 of the dog carrier.

When the tool is lowered to the desired location it is moved back upwardly, and the release dog enters the recess 38 at the next higher coupling 38a as shown in Figure 1 and is tripped by contact with the lower end of the upper tubing section 39. The toggle plate is rotated in a clockwise direction by the force exerted on the release dog until the pivot pin 34 is displaced to the right of the dead center position between the pin 25 and the link pin 31, the plunger rod then being moved upwardly relative to the body and lifting the carrier and stop dogs therewith. The stop dogs are moved toward expanded position by the engagement of their beveled inner upper ends with the expander surface to yieldingly engage the wall of the lower tubing section 40. The tool is then raised until the stop dogs reach the coupling recess, the stop dogs moving outwardly into said recess because of the camming action of the expander surface on their inner upper ends. The downwardly facing stop shoulders 41 of the dogs are then positioned to engage the upper end of the lower tubing section to prevent further downward movement of the tool in the tubing string (Figure 2). The release dog is retracted inside the body of the stop by the clockwise rotation of the toggle plate as shown in Figure 2.

When it is desired to remove the tool from the tubing string, an upward pull is exerted on the body, the stop dogs and the plunger rod being moved downwardly relative to the body against the biasing of the spring 32 on meeting obstructions, whereupon the stop dogs are cammed inwardly by the downwardly and outwardly beveled shoulders 42 at their upper ends. The tool is thus able to pass coupling recesses or obstructions as it is raised in the tubing string. The tool obviously may be raised by means of the standard flexible line running and pulling apparatus.

It will thus be seen that a new and improved tubing stop 10 has been provided with a plurality of stop dogs 19 which are movable to an expanded position to anchor the stop in position and against downward movement in the tubing string. It will also be seen that a tubing stop has been provided to be positioned in and removed from a well tubing by a flexible line.

It will further be seen that a new and improved tubing stop has been provided which may be positioned in open-ended well tubing to prevent the passage of other tools out through the end of said tubing.

It will be seen that the tubing stop may be positioned in a predetermined position in a well tubing string between spaced upwardly facing and downwardly facing stop shoulders.

It will be additionally seen that the stop includes stop dogs which are moved to expanded position by means of an over-the-center mechanism actuated on upward movement of said stop in the tubing string by a release dog

engageable with a downwardly facing shoulder in said tubing string.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

10. A stop for well devices for use in a well conductor having an internal upwardly facing shoulder and an internal downwardly facing shoulder spaced above said upwardly facing shoulder, said stop including: a body adapted to be lowered into said conductor, said body having a chamber; a plunger movably mounted in said chamber and having a lower end extending below said body; a dog carrier mounted on said lower end below said body; stop dogs carried by said dog carrier and mounted thereon for movement between retracted and expanded position; means on the lower end of said body for moving said dogs to expanded position when said plunger is moved upwardly relative to said body, said stop dogs when expanded being adapted to engage said upwardly facing shoulder of the well conductor to limit downward movement of the stop through the conductor; means on said body biasing said plunger upwardly; and locking means mounted on said body for preventing upward movement of the plunger, said locking means having release means engageable with the downwardly facing shoulder in the conductor for actuating said locking means to free said plunger upon upward movement of said body in the conductor.
20. A stop for well devices for use in a well conductor having an internal upwardly facing shoulder and an internal downwardly facing shoulder spaced above said upwardly facing shoulder, said stop including: a body adapted to be lowered into said conductor, said body having a chamber; a plunger movably mounted in said chamber and having a lower end extending below said body; a dog carrier mounted on said lower end below said body; stop dogs carried by said dog carrier and mounted thereon for movement between retracted and expanded positions; a mandrel having beveled shoulders at its lower end on the lower end of said body for engaging and moving said dogs to expanded position when said plunger is moved upwardly relative to said body, said stop dogs when expanded being adapted to engage said upwardly facing shoulder in the conductor to limit downward movement of the stop through the conductor; means on said body biasing said plunger upwardly; and locking means mounted on said body for preventing upward movement of the plunger relative to the body, said locking means having release means engageable with the downwardly facing shoulder in the conductor for actuating said locking means to free said plunger upon upward movement of said body in the conductor.
30. A stop for well devices for use in a well conductor having an internal upwardly facing shoulder and an internal downwardly facing shoulder spaced above said upwardly facing shoulder, said stop including: a body adapted to be lowered into said conductor, said body having a chamber; a plunger movably mounted in said chamber and having a lower end extending below said body; a dog carrier mounted on said lower end below said body; stop dogs carried by said dog carrier and mounted thereon for movement between retracted and expanded positions; a mandrel having beveled shoulders at its lower end on the lower end of said body for engaging and moving said dogs to expanded position when said plunger is moved upwardly relative to said body, said stop dogs when expanded being adapted to engage said upwardly facing shoulder in the conductor to limit downward movement of the stop through the conductor; means on said body biasing said plunger upwardly; and locking means mounted on said body for preventing upward movement of the plunger relative to the body, said locking means having release means engageable with the downwardly facing shoulder in the conductor for actuating said locking means to free said plunger upon upward movement of said body in the conductor.
40. A stop for supporting well devices in a well conductor having an internal downwardly facing shoulder and an internal upwardly facing shoulder therein, said stop including: a body having a longitudinal opening therein; central control means extending longitudinally of said body and slidably in said opening; a plurality of stop dogs mounted below said body and surrounding said control means; means on said control means pivotally supporting the lower ends of said stop dogs; said body having means engageable with the upper ends of said stop dogs for moving said stop dogs to expanded position upon longitudinal movement of said control means upwardly of said body; means biasing said control means for longitudinal upward movement relative to said body; locking means connected with said body and said control means for preventing longitudinal movement of said control means relative to said body; and means on said locking means engageable with said downwardly facing shoulder in the well conductor for releasing said locking means to permit longitudi-
50. A stop for supporting well devices in a well conductor having an internal downwardly facing shoulder and an internal upwardly facing shoulder therein, said stop including: a body having a longitudinal opening therein; central control means extending longitudinally of said body and slidably in said opening; a plurality of stop dogs mounted below said body and surrounding said control means; means on said control means pivotally supporting the lower ends of said stop dogs; said body having means engageable with the upper ends of said stop dogs for moving said stop dogs to expanded position upon longitudinal movement of said control means upwardly of said body; means biasing said control means for longitudinal upward movement relative to said body; locking means connected with said body and said control means for preventing longitudinal movement of said control means relative to said body; and means on said locking means engageable with said downwardly facing shoulder in the well conductor for releasing said locking means to permit longitudi-
60. A stop for supporting well devices in a well conductor having an internal downwardly facing shoulder and an internal upwardly facing shoulder therein, said stop including: a body having a longitudinal opening therein; central control means extending longitudinally of said body and slidably in said opening; a plurality of stop dogs mounted below said body and surrounding said control means; means on said control means pivotally supporting the lower ends of said stop dogs; said body having means engageable with the upper ends of said stop dogs for moving said stop dogs to expanded position upon longitudinal movement of said control means upwardly of said body; means biasing said control means for longitudinal upward movement relative to said body; locking means connected with said body and said control means for preventing longitudinal movement of said control means relative to said body; and means on said locking means engageable with said downwardly facing shoulder in the well conductor for releasing said locking means to permit longitudi-
70. A stop for supporting well devices in a well conductor having an internal downwardly facing shoulder and an internal upwardly facing shoulder therein, said stop including: a body having a longitudinal opening therein; central control means extending longitudinally of said body and slidably in said opening; a plurality of stop dogs mounted below said body and surrounding said control means; means on said control means pivotally supporting the lower ends of said stop dogs; said body having means engageable with the upper ends of said stop dogs for moving said stop dogs to expanded position upon longitudinal movement of said control means upwardly of said body; means biasing said control means for longitudinal upward movement relative to said body; locking means connected with said body and said control means for preventing longitudinal movement of said control means relative to said body; and means on said locking means engageable with said downwardly facing shoulder in the well conductor for releasing said locking means to permit longitudi-

nal movement of said control means, said stop dogs having stop shoulders thereon disposed to engage the upwardly facing shoulder in said conductor when in expanded position to prevent downward longitudinal movement of the stop in the conductor.

4. A well tool for use in a well string having an internal upwardly facing shoulder and an internal downwardly facing shoulder, said tool including: a tubular body having a longitudinal bore; a central member in said bore mounted for movement longitudinally therein; stop means carried by said central member movable laterally from a retracted position to a projecting position; laterally projecting boss means on said stop means engageable with the upwardly facing shoulder in said well string when said stop means is in said projecting position to limit downward movement of said well tool in said well string; expander means on said body engaging said stop means to move said stop means to said projecting position when said central member is moved longitudinally in one direction in said body; resilient means on said body engaging said central member for biasing said central member longitudinally in said one direction to move said stop means to projecting position; locking means connected with said body and said central member for preventing movement of said central member longitudinally of said body in said one direction from a position holding said expander means out of expanding engagement with said stop means; and means carried by said locking means engageable with the downwardly facing shoulder in said well conductor for releasing said locking means to permit longitudinal movement of said central member in said one direction; the boss means on said stop means having external beveled surfaces at the upper end thereof for camming said stop means inwardly toward retracted position upon meeting obstructions during upward movement of the tool in said well string.

5. A well tool including: a tubular body having a longitudinal bore; a central member in said bore movable longitudinally therein; stop means on said central member movable laterally from a retracted position to a projecting position; boss portions on said stop means engageable with an upwardly facing shoulder in a well string when said locking means is in said projecting position; wedge means on said body engageable with said stop means to move said stop means to projecting position when said central member is moved longitudinally to a first position; resilient means in said body engaging said central member for biasing said central member longitudinally in said body toward said first position; means on said central member preventing movement of said stop means beyond said projecting position; said central member having a reduced exterior portion permitting movement of said stop means to retracted position when said central member is in a second position in said body; an external beveled surface on said stop means whereby said stop means is cammed inwardly toward retracted position upon meeting obstructions; and release means in said body releasably holding said central member in said second position, said release means including a member engageable with a downwardly facing shoulder in the well string to release said release means and free said central member for movement in the body toward said first position upon upward movement of the well tool in said well string.

6. A well tool including: a tubular body having a longitudinal bore; a central member in said bore movable longitudinally therein; stop means on said central member movable laterally from a retracted position to a projecting position; boss portions on said stop means engageable with an upwardly facing shoulder in a well string when said stop means is in said projecting position; wedge means on said body engageable with said stop means to move said stop means to projecting position when said central member is moved longitudinally to a first position; resilient means in said body engag-

ing said central member for biasing said central member longitudinally in said body toward said first position; means on said central member preventing movement of said stop means beyond said projecting position; said central member having a reduced exterior portion permitting movement of said stop means to retracted position when said central member is in a second position in said body; an external beveled surface on said stop means whereby said stop means is cammed inwardly toward retracted position upon meeting obstructions; and release means in said body releasably holding said central member in said second position; said release means having a release dog projecting outwardly from said body and engageable with a downwardly facing shoulder in said well string on upward movement of said tool in said well string to actuate said release means to permit movement of said central member toward said first position.

7. A well tool including: a body having a longitudinal bore; a central member in said bore movable longitudinally therein; a cup-shaped member on the lower end of said central member; stop means swingably mounted in said cup-shaped member for movement of the upper ends of said stop means outwardly from a retracted position to a projecting position; outwardly extending boss portions providing a shoulder thereon on said stop means engageable with an upwardly facing shoulder in a well string when said stop means is in said projecting position; expander means on said body engageable with the upper ends of said stop means to move said stop means to said projecting position when said central member is moved longitudinally upwardly in said body; said expander means being movable out of expanding engagement with said stop means when said central member is moved longitudinally downwardly in said body whereby said stop means may move to said retracted position; resilient means on said body engaging and biasing said central member longitudinally upwardly in said body; means on said stop means and said cup-shaped member limiting outward pivotal movement of the upper ends of said stop means; link means in said body connected between said body and said central member and releasably holding said central member in its lower position against the biasing force of the resilient means; release means connected with said link means engageable with a downwardly facing shoulder in the well string upon upward movement of the well tool in said well string for moving said link means from position holding said central member in its lower position relative to said body to free the resilient means to move said central member upwardly to its upward position in said body whereby the stop means are moved to expanded position.

8. A well tool including: a body having a longitudinal bore and a lateral aperture communicating with said bore; a central member in said bore movable longitudinally therein, the lower end of said central member extending below said body; resilient means in said body engaging said body engaging said central member and biasing said member for longitudinal movement upwardly in said body; link means in said bore connected to said central member and said body and releasably holding said central member in a lower position on said body against the upward biasing force of said resilient means; release means connected with said link means and having one end extending outwardly and upwardly of said body through said aperture when said central member is in said lower position; spring means on said link means engageable with and biasing said release means outwardly of said body; said one end of said release means being engageable with a downwardly facing shoulder in the well flow conductor on upward movement of the well tool to free said link means for movement from holding position to a released position to permit said central mem-

ber to move upwardly in said body; said link means reTRACTING said release means within said body when said central member is moved to said upper position; cup means on said central member below said body; stop members pivotally mounted at their lower ends in said cup means and extending upwardly therefrom whereby the upper ends of said stop members may move laterally from a retracted position to an expanded position; expander means on said body engageable with said stop members when said central member is moved upwardly 10 whereby said stop members are moved to said expanded position; and outwardly extending boss portions having

downwardly facing shoulders on the upper ends of said stop members.
